UNITED STATES PATENT OFFICE.

OLOF OHLSON, OF NEWTON, MASSACHUSETTS, ASSIGNOR TO WALTHAM WATCH COMPANY, OF WALTHAM, MASSACHUSETTS, A CORPORATION OF MASSACHUSETTS.

WALL-CLOCK.

1,379,713.

Specification of Letters Patent. Patented May 31, 1921.

Application filed August 16, 1917. Serial No. 186,492.

To all whom it may concern:

Be it known that I, OLOF OHLSON, a citizen of the United States, residing at Newton, in the county of Middlesex and State 5 of Massachusetts, have invented new and useful Improvements in Wall-Clocks, of which the following is a specification.

The present invention relates to time pieces or clocks and has for its object to provide, 10 first, the combination of a frame mounting a dial, and a movement, the frame and movement being of such proportions and so arranged as to permit of the time piece being hung upon or placed against a wall in 15 a manner similar to that in which a picture or mirror is commonly placed or hung; and second, to provide means for winding, and setting the hands of, a time piece so made. The novel features and improvements in 20 which the invention particularly consists appear from the following description in detail of one embodiment of my invention, in connection with the drawings which illustrate the described embodiment. In the 25 drawings,

Figure 1 is a front elevation of a clock containing the present invention.

Fig. 2 is a rear elevation of the same.

Fig. 3 is a detail view in cross section 30 on line 3—3 of Fig. 2 of the winding and setting device which forms a part of the invention.

Fig. 4 is a view of the same device or mechanism showing the parts thereof in 35 the position assumed when the clock is being wound.

Fig. 5 is a similar view of the same mechanism showing the parts in the position wherein they are placed for setting the 40 hands of the clock.

Fig. 6 is a cross section on line 6—6 of Fig. 4.

Fig. 7 is a sectional view in detail of 45 the holding member or clutch which co-operates with the winding and setting stem for holding the same in the different positions which are taken for winding and for setting, respectively.

The combination includes a frame 11 in 50 which is mounted a face or dial 12, the latter being visible at the front of the frame and being preferably designed so as to fit the rectangular space outlined by the frame. This is the preferred feature of ornamental

design, but may be modified without departing from the invention; and so far as the latter is concerned the frame may be of any shape or outline and the dial may be of any corresponding outline, or may be circular without regard to the particular 60 shape of the frame, according to the common practice in clock making. The case inclosing the movement or time mechanism is shown at 13 in Fig. 12. Such movement and the inclosing case are of relatively very 65 small dimensions both diametrically as well as axially, that is, from front to rear, in proportion to the dimensions of the frame, whereby the movement and its inclosing case project only a very slight extent, or not 70 at all, from the plane of the back of the frame. This arrangement and these proportions enable the clock as a whole to be hung upon a wall in the same manner that a frame picture or mirror is ordinarily 75 hung, or may be otherwise placed flat or nearly flat against a wall and either secured to the wall or permitted to lean against the same. The movement itself may be any 80 standard watch or clock movement having an escape mechanism, such as the familiar lever escapement, which will operate correctly regardless of the position in which the movement is placed. I have used for this purpose a standard eight-day spring- 85 driven lever escapement watch movement, and may employ any other equivalent or similar movement, wherefore I have deemed it unnecessary to illustrate the movement in detail. That staff of the movement which 90 ordinarily drives the hands is carried through the center of the dial and upon it is mounted the minute hand 14 and the hour hand 15, in the usual manner.

Another part of the invention consists in 95 winding and setting means for the clock movement designed and adapted to be used in connection therewith and with a frame which is materially wider than the movement and is placed close to a wall. This 100 winding and setting means is shown in Fig. 2 in approximately the correct proportions and preferred relation which it bears to the movement and the frame, and in Figs. 3 to 7 inclusive it is shown in detail on an enlarged scale. The main parts of this mechanism comprise a stem 16 and a setting crown 17, the stem being mounted at its 105

outer end in a bracket 18 on the frame in which it is both rotatable and movable axially, and its inner end extends into the case 13 and is engaged with the winding and hand setting mechanisms with which the movement is provided. The last mentioned mechanisms are or may be the same as any of the mechanisms for this purpose commonly used in watch movements and similar 10 timepieces, and are therefore not shown. It is sufficient for a complete understanding of this invention to state that when the stem is displaced axially in one direction it is connected to the hand setting mechanism and 15 may be operated by rotation of the crown 17 to set the hands, while when displaced in the opposite direction it is coupled to the winding mechanism and may be similarly operated to wind up the main spring of the 20 timepiece. The crown is engaged with the stem in a manner permitting axial movement and is arranged at the outer side of the bracket, that is, the side toward the adjacent edge of the frame, so that it may be 25 displaced beyond the periphery of the frame for either winding or setting, and when not being operated it may be placed within such periphery and so concealed from sight, since the bracket is located far enough inward 30 from the nearest part of said periphery to permit placement of the crown in this position. For the purposes of this description it will be assumed that displacement of the stem outward from the movement puts it in 35 condition for setting the hands, and displacement toward the movement puts it in the condition for winding; this assumption being made without intent to limit the invention or to exclude from the scope of the 40 protection herein claimed a combination in which the reverse condition is found, that is, one in which setting is accomplished by pushing the stem inward and winding by pulling it outward.

45 Referring now to Figs. 3 to 7 it will be seen that the crown 17 is fixed upon the outer end of a sleeve 19 which is slidable, both axially and rotatably upon an interior sleeve 20, which latter is fixed in the bracket 50 18 and projects from such bracket toward the outer boundary of the frame. The bracket has a base flange 21 which is secured by screws 22 or other means suitable for the purpose, to the frame. The stem 16 passes through the inner sleeve 20 and has 55 a threaded extension 23 on its end, upon which is fixed a non-circular head 24. The latter has external ribs 25 which are contained in complementary longitudinally extending grooves 26 in the interior of the outer sleeve 19. Conveniently, and preferably, the head 24 is an ordinary hexagonal nut, the corners of which form the ribs, while the grooves 26 in the sleeve 19 are formed

and spaced to fit these corners. This permits the crown to be moved in and out while always being connected to the stem so as to transmit rotation thereto. On the inner end of the sleeve is an interior lip 19^a arranged to engage the head 24 when the crown is 65 pulled out, whereby both to enable movement of the stem into setting position by the crown, and to prevent separation of the crown altogether from the stem.

The stem is grooved at one part so as to 75 form a conical or tapered surface 27 adjoining an abrupt shoulder 28, and an oppositely tapered portion 29 adjoining an annular recess 30. These beveled portions 27 and 29 are segments of cones which are 80 set base to base. With these cone segments coöperates a clutch or holder 31, shown in detail in Fig. 7, and preferably formed as a sleeve of elastic metal divided by longitudinal cuts 32 into a plurality of spring 85 tongues, the outer ends of which are bent toward the axis of the sleeve so as to form gripping jaws 33. The opposite end of the clutch sleeve is provided with a lip 35 which is confined between a rib 36 and a flange 37 90 on a holding sleeve 38, which latter is externally threaded so as to fit internal screw threads in the sleeve 20, and is provided with slots 39 to receive a screw-driver or other tool used for screwing it in place. 95

From the foregoing description the mode of use of the device will be readily apparent. The ends of the clutch jaws 33 co-operating either with the cone segment 29 as shown in Figs. 3 and 4, or with the cone 100 segment 27 as shown in Fig. 5, hold the stem in either the winding position or the hand-setting position. With the stem in either of these positions the crown can be pulled out beyond the edge of the frame, as 105 shown by Figs. 4 and 5, and can be rolled between the thumb and finger of a person's hand so as to rotate the stem and either wind the clock spring or set the hands. When not being used for either purpose the crown is 110 pushed in as shown in Figs. 2 and 3, when it lies behind the edge of the frame and is concealed from the view of one in front of the clock. When in the latter position the crown lies so close to the frame that it can not be 115 manipulated, this relation being required in order that the clock may be placed against a wall in the manner already described.

What I claim and desire to secure by Letters Patent is:

1. A wall clock comprising a frame, a dial mounted in said frame, a time movement mounted on the back of the frame, a winding stem projecting laterally from said movement toward one edge of the frame, and a 120 crown on said stem mounted close to the rear plane of the frame normally within the adjacent edge thereof and having a sliding

connection with the stem whereby it may be placed outside of such edge for manipulation.

2. A wall clock comprising a frame, a dial mounted in said frame, a time movement mounted on the back of the frame, a winding and setting stem projecting laterally from said movement toward an edge of the frame and being displaceable endwise from position for winding to a different position for setting, and vice versa, yieldable means arranged to hold said stem in either position, and a crown mounted on said stem in rotation-transmitting engagement therewith, and being also shiftable endwise thereon; the outer termination of the stem being within the edge of the frame toward which it projects at a position permitting the crown to be moved beyond said edge for winding or setting, and to be placed at other times within such edge, whereby it is hidden by the frame.

3. A wall clock comprising a frame, a dial mounted in said frame, a time movement mounted on the back of the frame, a winding and setting stem projecting laterally from said movement toward an edge of the frame to a termination short of such edge and being displaceable endwise from position for winding to a different position for setting, and vice versa, yieldable means arranged to hold said stem in either position, a crown mounted on said stem in rotation-transmitting and sliding engagement therewith, being thereby movable across said edge, and complementary stops on the crown and stem limiting the relative endwise movement of the crown and enabling force applied axially to the latter to displace the stem from either of its positions to the other.

4. A wall clock comprising a frame, a dial mounted therein, a time movement mounted on the back of the frame entirely within the periphery of the latter, a bracket mounted on the back of the frame near one edge thereof, a winding stem extending from said movement to said bracket and supported as to its outer end by the latter, a crown having a rotation transmitting and axially slidably engagement with the stem arranged at the outer side of the bracket; the location of the bracket being far enough inward from the adjacent frame edge to permit placement of the crown within such edge, where it is hidden from view, and the axial movement of the crown being sufficient to enable it to be projected across such edge into accessible position for winding.

5. A clock comprising a frame, a clock movement smaller than the frame mounted thereon, a winding and setting stem passing from said movement toward an edge of the frame, a bracket secured to the frame supporting and guiding said stem, the stem being movable axially into either of two positions for respectively winding, and setting the hands of the movement, a clutch mounted on said bracket coöperating with the stem for holding the same in either position and yieldingly resisting displacement therefrom, and a crown mounted on said stem in rotation-transmitting connection therewith, being normally within the perimeter of the frame, but movable lengthwise of the stem outside of such perimeter for manipulation.

6. A winding and setting mechanism for timepieces comprising in combination with a frame, a bracket on the frame, an axially displaceable rotatable winding and setting stem passing through said bracket and supported thereby, a setting crown and combined sleeve having provision for axial movement relatively to said stem, a head on said stem engaged with said sleeve so as to prevent relative rotation between the two but to permit relative longitudinal movement of the crown in addition to the movement necessary to displace the stem axially, and means for retaining said stem in either of two positions axially displaced from one another.

7. A clock comprising a frame, a dial inclosed by said frame, a clock movement centrally mounted on the back of the frame and having a diameter materially less than the width of the frame, a winding and setting stem projecting from the movement toward an edge of the frame but terminating short thereof, a non-circular head secured to the stem, a sleeve complementary internally to the exterior of the head, whereby it is prevented from rotating about the head but is enabled to slide lengthwise thereon, a crown on the outer end of said sleeve, and an interior lip on the inner end of the sleeve adapted to engage the head when the crown is moved outward; the crown being movable to a position back of the frame within the nearer edge thereof, and the sleeve being longer than the distance of the head from said edge, whereby the crown may be moved outward into a position accessible for manipulation.

In testimony whereof I have affixed my signature.

OLOF OHLSON.
